UNITED STATES PATENT OFFICE.

ALVA J. GROVER, OF COUNCIL BLUFFS, IOWA.

WASHING-MACHINE.

1,211,436.

Specification of Letters Patent.

Patented Jan. 9, 1917.

Application filed April 5, 1915. Serial No. 19,389.

To all whom it may concern:

Be it known that I, ALVA J. GROVER, a citizen of the United States, and a resident of Council Bluffs, in the county of Pottawattamie and State of Iowa, have invented certain new and useful Improvements in Washing-Machines, of which the following is a specification.

My invention relates to washing machines 10 of the class having vertically reciprocating agitating means operating within a receptacle containing the articles to be washed.

It is the object of my invention to provide in a washing machine a vertically reciprocating pounder, yielding actuating means for said pounder whereby the same may be caused to press equally upon varying amounts of material, means for moving the pounder horizontally toward and away from 20 the center of an associated tub, and means connected with the actuating means for causing a rotary movement of the tub, whereby the pounder will be operated successively in the various parts of the tub.

25 A structure embodying my invention is illustrated in the accompanying drawings, wherein—

Figure 1 is a side view of the machine, parts being broken away, Fig. 2 is a horizontal sectional view on the plane of the line $x-x$ of Fig. 1, Fig. 3 is a detail vertical sectional view of the drive mechanism on the line $y-y$ of Fig. 1, Fig. 4 is a detail end elevation of the drive mechanism, and Fig. 35 5 is a plan view of the machine.

In the structure shown I provide a suitable frame having a base-portion 1 which is held at a suitable height by legs 2 (shown broken off in the drawings). At one end of 40 the machine there is an elevated table 3 carried by a supporting-frame 4 which connects it with the base-portion 1. On top of the table 3 is secured the fixed frame 5 of the drive mechanism, said frame 5 having 45 bearings formed therein for a horizontal main-shaft 6 and a vertical shaft 7. On the inner end of the main-shaft is a bevel pinion 8 which meshes with a bevel-gear 9 secured on the shaft 7 so that said shaft may be 50 driven by rotation of the main-shaft 6. On the outer end of the main-shaft 6 is a suitable pulley or fly-wheel 10 which has a handle 11 so that it may be turned by hand. The lower part of the vertical shaft 7 extends 55 down through the table 3 and the lower end of the shaft is journaled in a

suitable bearing carried on one of the cross pieces of the base 1. On one end of the base 1 a tub 12 is revolvably supported by means of rollers 13 mounted on the cross pieces of the base, as shown. On the central portion of the bottom of the tub there is secured a toothed wheel 14 of which the hub-portion extends into a bearing on the base, so as to keep the tub centered on a fixed vertical axis. On the hub-portion of the wheel 14 is pivoted a pawl-arm 15, and to the end of said arm is pivotally connected the end of a rod 16. The other end of said rod forms an eccentric-strap which fits upon a small eccentric 17 which is secured to the shaft 7 just above the bearing for the lower end of said shaft. A pawl 18 is pivoted on the outer end of the arm 15 and normally engages the peripheral part of the wheel 14, as shown in Fig. 2. A lever 19 is pivotally connected with the pawl by means of a link 20, and may be used to move the pawl out to a position at which it will not engage the wheel. Rotation of the vertical shaft 7 imparts a reciprocating movement to the connecting-rod 16, and to the pawl-arm and pawl, so that when the pawl is in position to engage the wheel 14, the latter is actuated thereby and an intermittent rotative movement is imparted to the tub.

A swing-frame 21 is provided, having at one end thereof portions which are pivotally connected with the shaft 7 above the upper and lower bearings for said shaft in the fixed frame 5. In the swing-frame are formed bearings for a horizontal crank-shaft 22. A bevel gear 23 is secured on the end of the shaft 22 adjacent to the shaft 7 and meshes with a similar gear 24 on said shaft 95 7 so that the crank-shaft is driven from the vertical shaft.

At the free end of the swing-frame 21 there are upper and lower projecting arms 25 and 26 through which the pounder-rod 27 is vertically slidable. On the lower end of the pounder-rod within the tub 12 is a hollow conical pounder 28, the same being of the type commonly known as a "vacuum" washer. On the upper end of the rod 27 a hand-wheel 29 is screwed thereon, and said hand-wheel has hooks 30 engaging an annular lip on a collar 31 which is slidably disposed on the rod below the wheel. To said collar is connected one end of a coil spring 32 which is disposed around the rod and of which the lower end is connected with the

stud-collar 33. Said stud-collar is also slidably disposed on the rod 27, and a connecting-rod 34 extends from the collar to a crank 35 on the end of the crank-shaft 22, so that 5 rotation of said shaft imparts a vertically reciprocating movement to the collar. Ordinarily the entire vertical movement of the stud-collar is imparted to the pounder-rod, but if there be an excessive resistance to the 10 downward movement of the pounder, such as would be caused by an unusual amount of material in the tub, the movement of the stud-collar, or a part of such movement, will be expended in stretching the spring 32. 15 The spring 32 is so proportioned that it may be elongated sufficiently to take up almost the entire movement of the stud-collar, and it is thus impossible to cause an excessive stress upon the driving mechanism should 20 there be an unusual amount of clothing placed in the tub, or if the materials being washed therein should become bunched beneath the pounder. The tension of the spring 32 may be varied by screwing the hand-wheel 29 up or down on the rod, and the device is thus adjusted so as to operate most effectively upon varying amounts of 25 material in the tub.

On the lower side of the swing-frame 30 there is revolvably mounted a crank-wheel 36 which has a series of teeth on the upper side of the rim thereof, as shown. On the lower side of said wheel there is an eccentrically-disposed crank-pin 37 which fits 35 slidably in a rectilinear channel formed in a plate 38 which is secured to the table 3 beneath the swing-frame, the channel in the plate extending radially to the vertical shaft 7. The wheel 36 has an intermittent 40 rotative movement imparted thereto by means of an eccentric 39 carried on the crank-shaft 22. A strap 40, disposed around the eccentric, is pivotally connected with the horizontal arm of a bell-crank 41 which is fulcrumed on a lug 42 on the 45 swing-frame. The vertical arm of the bell-crank carries a pawl 43 adapted to engage the teeth on the wheel, so that the reciprocating movements imparted to the pawl by the eccentric and bell-crank intermittently 50 actuate the wheel. As the wheel 36 is revolved, the crank-pin 37, which remains constantly in the channel in the plate 38, causes the frame 21 to swing between the extreme 55 positions shown by full and dotted lines in Fig. 5, or so that the pounder is moved horizontally from positions near the sides of the tub to positions near the center thereof.

60 The described swinging movement of the frame 21, combined with the rotary movement of the tub and the vertical movements of the pounder, causes the pounder to work successively in all parts of the tub, and 65 materials in any part of the tub will, thus,

in the course of a cycle of operations of the actuating mechanism, be brought beneath the pounder. Should it be desired to stop the swinging movement of the frame 21, the pawl 43 may be lifted out of operative 70 relation to the crank-wheel 36 by means of a rod 44 which extends to the upper part of the frame and is connected with a small cam-lever 45. Said lever is formed so that by turning the same up to a vertical position the rod 44 is raised and the pawl lifted 75 out of contact with the teeth on the crank-wheel.

From the foregoing, the structure and operation of the machine will be clearly apparent, and it will appear also that various changes and modifications of the mechanism may be made without departing from the spirit of my invention.

Now, having described my invention, 85 what I claim and desire to secure by Letters Patent is:

1. In a washing machine, vertically reciprocating agitating means, a tub associated therewith and rotatable on a vertical 90 axis, a swing-frame carrying the agitating means and movable in a horizontal plane to carry the agitating means in a path approximately radial to the axis of the tub, and connected driving mechanism for reciprocating the agitating means, rotating 95 the tub, and swinging the frame.

2. In a washing machine, vertically reciprocatable agitating means, a pivoted horizontally swingable frame carrying said agitating means, and connected driving means 100 for reciprocating the agitating means and for swinging said frame in alternating directions about the pivotal axis thereof.

3. In a washing machine, a fixed frame, 105 a vertical shaft journaled therein, a movable frame pivoted on said shaft, a horizontal shaft journaled in said movable frame and extending radially to the vertical shaft, gearing operatively connecting said horizontal and vertical shafts, a rod slidable vertically in the movable frame, means connecting said rod and the horizontal shaft for reciprocating the rod, and means actuated by the horizontal shaft for swinging 110 the movable frame to reciprocate the same about the axis of the vertical shaft.

4. In a washing machine, a tub rotatable on a vertical axis, agitating means disposed within the tub, a movable frame carrying 115 said agitating means, said frame being pivoted on a vertical axis and being swingable thereon to move the agitating means horizontally toward and away from the axis of the tub, and connected driving means for 120 actuating the agitating means, rotating the tub, and swinging the movable frame alternately toward and away from the tub-axis.

5. In a washing machine, a fixed frame, 125 a movable frame pivoted on the fixed frame 130

so as to be swingable horizontally about a vertical axis, a horizontal crank-shaft journaled in said movable frame, means for rotating said shaft, a rod slideable vertically 5 in the movable frame, means connecting said rod and crank-shaft whereby the rod may be reciprocated vertically by rotation of said shaft, a crank-wheel mounted on a movable frame so as to be revolute on a vertical axis, means connected with the crank-shaft for rotating said wheel, a plate 10 connected with the fixed frame and extending adjacent to the crank-wheel, and a pin

on the crank-wheel disposed eccentrically thereto and extending into a rectilinear 15 channel in said plate, the channel being substantially radial to the axis of the movable frame.

In testimony whereof I have hereunto subscribed my name in the presence of two 20 witnesses.

ALVA J. GROVER.
